UNITED STATES PATENT OFFICE.

WILLIAM J. BENSON, OF PHILADELPHIA, PENNSYLVANIA.

CARBURETER.

1,260,132.

Specification of Letters Patent. Patented Mar. 19, 1918.

Application filed December 13, 1915. Serial No. 66,587.

To all whom it may concern:

Be it known that I, WILLIAM J. BENSON, a citizen of the United States, residing at Philadelphia, in the county of Philadelphia 5 and State of Pennsylvania, have invented new and useful Improvements in Carbureters, of which the following is a specification.

This invention relates to improvements in carbureters, and an object thereof is to provide an improved structure whereby a proper proportion of combustible fuel is automatically supplied to an engine in direct ratio to the speed at which the latter is operating.

Another object of the invention is to provide a carbureter with a plurality of air and fuel admitting openings in communication with a mixing chamber, means being provided for automatically and independently 10 opening or closing these openings in accordance to the fuel demands of the engine.

A further object of the invention is to provide a carbureter of this character which will eliminate the necessity of using coiled 15 springs, float valves, spray nozzles and various other forms of sensitive and fragile mechanisms, which are now generally found upon the usual forms of carbureters, thereby providing a carbureter which, while 20 highly efficient, is of strong durable construction, of few and simple parts, and capable of withstanding all shocks or jolts 25 without in any way affecting the operation thereof.

A still further object of the invention is to provide a carbureter in which the liquid fuel therein cannot be reached by burning 30 gases resulting from the engine back-firing, thereby avoiding explosions or fires.

In the further disclosure of the invention 35 reference is to be had to the accompanying drawings, constituting a part of this specification, in which similar characters of reference denote corresponding parts in all of 40 the views, and in which:—

Figure 1 is a vertical diametrical sectional view of the carbureter comprising one of the preferred forms of the present invention.

Fig. 2 is a side elevation of the same, 50 Fig. 3 is a top plan view, Fig. 4 is a horizontal sectional view on the line 4—4 of Fig. 1.

Fig. 5 is a similar view on the line 5—5 of Fig. 1, 55

Fig. 6 is a bottom plan view, and

Fig. 7 is a fragmentary section on the line 7—7 of Fig. 1.

Referring more particularly to the drawings, the numeral 10 designates the casing 60 of a carbureter comprising the present invention. The casing is of tubular formation, being formed with upper and lower sections 11 and 12, which are threadedly connected as indicated at 13. The upper 65 extremity of the casing 11 is suitably connected with the intake manifold of an internal combustion engine (not shown), and the interior thereof is provided with the usual form of throttle valve 14, which regulates the flow of the combustible mixture, generated by the carbureter, to the engine. The valve 14 is operated by the usual lever 15.

The hollow interior 16 of the section 12 75 is utilized as a mixing chamber wherein the fuel and air are commingled prior to being drawn into the engine; the special method of admitting the combustible products into the mixing chamber 16 will be set forth with 80 particularity hereinafter, as it is upon this feature that the novelty of the present invention resides.

The lower extremity of the section 12 is slightly enlarged to provide an annular fuel 85 well 17 fed by a valved supply pipe 18 extending from a suitable source of fuel supply. A plurality of ports 19 connect the well 17 with the mixing chamber 16, thereby providing passages for discharging fuel 90 from the well to said mixing chamber. Air ducts or openings 20 are also formed in the section 12, to provide passageways for the admission of air into the mixing chamber, said openings 20 being preferably arranged 95 in substantially vertical alignment with the ports 19.

Secured as at 21 to the wall of the mixing chamber 16, and completely covering the ports and openings 19 and 20 respectively, 100 are leaf springs 22, in this instance consisting of springs *a*, *b* and *c*, which differ in resiliency.

In reference to the operation of the above described parts, the suction created by the 105 action of the operating engine is trans-

mitted directly to the mixing chamber 16 containing the port covering springs 22. If the engine is running at a reduced rate of speed the suction derived therefrom will be of sufficient strength to actuate the spring *c* deflecting the latter outwardly from its point of suspension 21 and simultaneously uncovering the respective admission ports of the carbureter. This action results in admitting a quantity of air and fuel into the mixing chamber, where the two fluids are commingled and drawn into the engine cylinders at the proper proportion for the operation of the engine, when the latter is running relatively slowly.

Increased suction will pull the spring *c* inwardly until it contacts with a stop member 23, which yieldingly resists its movement resulting in the operation of the spring *b* so as to open the ports covered thereby and thus supplying an additional amount of fuel to the engine which will meet the increased fuel demands thereof. When the demand of the engine still increases the resistance of the spring *a* will be overcome and the carbureter will then be supplying the engine with combustible mixture to its fullest capacity. Incidentally, it is well to state that there are no rests or pauses between the actions of the springs 22. In other words as soon as the spring *c* has reached its limit of movement, and the engine is accelerating its speed, the spring *b* will synchronously open with the stopping of the spring *c*, thereby permitting of a continuous fuel feed to meet the requirements of the engine, eliminating the intermittent features of fuel supply which characterizes the operation of the usual carbureter.

The air supplied to the air inlet openings 20 is preheated before it enters the mixing chamber 16. This is accomplished by placing a casing 25 around the lower section 12, the lower edge of the casing resting upon the enlarged lower end of said section 12 and having its upper extremity secured as at 26 to an enlarged collar 27 formed on the section 11. A horizontally extending duct 28 is integrally formed with the casing 25 and extends within close proximity of the exhaust manifold of an engine so that the air drawn through the duct 28, into the casing 25, will be in a heated condition. A rotatable collar 29, provided on the duct 28, is formed with openings 30 for registration with similar openings formed in said duct. These openings are placed in alinement when colder air is wanted in the carbureter, or for combining the air received around the exhaust of the engine with that of a colder degree for producing certain results in the carbureter.

The fuel supply of the carbureter is also capable of adjustment and as shown the

supply of fuel which enters the mixing chamber 16 from the well 17 by way of the ports 19, is regulated by needle valves 31. The latter consist merely of threaded hand screws 32, threaded into openings 33 formed in the section 12, in alinement with the ports 19. Tapered ends 34 are provided on each of said valves so that upon the manipulation thereof the tapered ends will cooperate with the ports 19 to either close, partially obstruct or to fully open the same, thus controlling the flow of fuel therethrough. A lock nut 35 is placed upon said valve to prevent accidental displacement thereof after being regulated.

Hinged to the bottom of the lower section 12 is a swinging door 36 the primary purpose of which is to prevent air from being drawn into the mixing chamber 16 from points other than the openings 20; a spring 37 exerts an upward pressure on the door to maintain the same in a normally closed position. If the engine should "back-fire" the force of the explosion will be sufficient to overcome the action of the spring 37, thereby opening the door 36 and permitting the effects of the explosion to pass harmlessly off. It will be seen that the action of such explosion will cause the springs 22 to be pressed tightly against the wall of the mixing chamber, thereby positively preventing accidents, such as fire, occurring by the ignition of fuel by the burning gases.

It will thus be seen that there is provided mechanism in which the objects of this invention are achieved and all the advantageous features above mentioned are, among others, present. The device is positive in action, of few parts and simple construction. The parts are so disposed as to prevent crowding, but, nevertheless, are compactly arranged so as to minimize the size of the carbureter. The several changes of relation can be accomplished expeditiously with a small amount of labor and when the parts are once set the mechanism is of such character as to be insured against accidental displacement, thus rendering the action of the carbureter thoroughly reliable.

Having described the invention what is claimed as new is:—

1. In a carbureter, a mixing chamber formed with a circular series of sets of admission ports, each set of ports comprising a fuel inlet port and an air inlet port, and an inwardly yieldable closing member controlling both ports of each set, each controlling member differing from all of the others in the degree of resistance to the port opening movement thereof.

2. In a carbureter, a mixing chamber having a circular series of sets of admission ports, each set comprising an air inlet port and a fuel inlet port, an inwardly opening

resilient valve for each set of ports, and a yieldable stop member for each of said valves arranged normally in spaced relation to and out of contact with the respective valve and adapted after a predetermined degree of movement of the valve to yieldingly resist the further opening movement

thereof, each of said valves varying from all the others in its degree of resiliency.

In testimony whereof I affix my signature **10** in presence of a witness.

WILLIAM J. BENSON.
